UNITED STATES PATENT OFFICE.

WILLIAM H. RICHTER, OF PHILADELPHIA, PENNSYLVANIA, ASSIGNOR TO ARTHUR ATWATER KENT, OF ARDMORE, PENNSYLVANIA.

INTERRUPTER MECHANISM.

1,348,185.

Specification of Letters Patent. Patented Aug. 3, 1920.

Application filed June 28, 1919. Serial No. 306,850.

To all whom it may concern:

Be it known that I, WILLIAM H. RICHTER, a citizen of the United States, residing in the city and county of Philadelphia, State of 5 Pennsylvania, have invented new and useful Improvements in Interrupter Mechanism, of which the following is a specification.

My invention relates to structure for interrupting an electric circuit for any purpose, and particularly for interrupting the 10 ignition circuit of an internal combustion motor.

My invention resides in apparatus of the 15 character referred to in which there is employed in combination with interrupter mechanism, operating either upon the open or closed circuit principle, or upon any other suitable principle, condenser structure comprising a condenser embedded in or inclosed 20 within a housing or coating of insulating material, forming a condenser unit having terminals and means for securing the condenser unit to a suitable plate or base member.

25 My invention resides further in structure of the character referred to wherein the condenser unit itself supports one of the contacts, preferably the stationary contact, of the interrupter mechanism. My invention 30 resides in structure of the character herein-after described and claimed.

For an illustration of one of many forms my invention may take, reference is to be had to the accompanying drawing, in which:

35 Figure 1 is a plan view of structure embodying my invention.

Fig. 2 is a side elevational view of the same.

40 Fig. 3 is a horizontal sectional view, partly in plan, taken on the line 3—3 of Fig. 4.

Fig. 4 is a vertical sectional view, partly in elevation, taken on the line 4—4 of Fig. 3.

45 Fig. 5 is a diagrammatic view of one of various circuit arrangements in which my apparatus is utilizable.

Referring to the drawing, there is therein 50 illustrated interrupter structure more or less similar to that illustrated in Letters Patent of the United States No. 1,289,036, granted December 24, 1918 to A. A. Kent, the same being my preferred structure with the understanding, however, that my invention is not limited thereto. The structure illustrated is of a so-called closed circuit type in that the 55 interrupter contacts are normally closed or

closed for a relatively long period and separated to cause circuit interruption for a relatively shorter period. In this connection, however, it shall be understood that my invention is equally applicable to interrupters 60 operating upon the so-called open circuit principle, wherein the circuit is momentarily closed and is normally open and is, in fact, open for a relatively great portion of the time.

In the drawing, the metal support, base or plate 1 is provided with a hub extension 2 in which is journaled the timer shaft or cam shaft 3 having adjacent its upper end the cam 4, or regular polygonal outline having an apex for each cylinder of the internal combustion motor. As well understood in the art, the shaft 3 generally is driven at one-half the speed of the crank shaft of the motor, particularly when it is of the type 75 employing four strokes per cycle. The cam structure 4 forms an enlargement or shoulder upon the shaft 3, and under the lower edge of the cam structure projects the plate 5, held to base 1 by screws 6, which prevents the shaft 3 from dropping downwardly, as viewed in Fig. 2, away from the plate 1 through the hole 7 therein.

Embracing the hub 2 may be provided the ring clamp 8, drawn tight by screw 9, and carrying the lever 10 having a hole 11 to which may be connected any suitable structure for rotating the hub 2 and therefore the plate 1 and the parts carried thereby suitably to advance or retard the spark by shifting the phase or time relation of the cam follower, carrying the movable interrupter contact, with respect to the cam 4 which rotates in definite phase or time relation with respect to the crank shaft of the engine or 95 motor.

The cam follower comprises the movable contact arm 12 to which is secured the spring 13 secured to and supported by the upstanding bracket 14 secured by screw 15 to the 100 plate 1. The movable interrupter contact 16 is carried by and in electrical communication with the arm 12 and is therefore in electrical communication with the plate 1, which in turn is in electrical communication with 105 the metal frame or mass of the engine or vehicle carrying the same, the contact 16 being therefore "grounded," as understood in this art. This grounding of the contact 16 it will be understood is merely a preferred arrangement. 110

ment, and is not limitive of my invention. At the end of the arm 12 is provided a shoe or tip 17 of any suitable material, as vulcanized or indurated fiber, which is actuated by the rotating cam 4 periodically to separate contact 16 from and allow restoration thereof by spring 13 into engagement with the coöperating stationary contact 18 carried by and in electrical communication with the adjustable metallic member 19 having the slot 20 through which extends the screw 21 securing the member 19 to the condenser unit 22.

The condenser unit 22 comprises a condenser 23 of any suitable type, for example, sheets of tin foil or equivalent separated by suitable flexible dielectric material, as paper, impregnated paper or cloth, or equivalent, and rolled up into a compact roll or mass.

To the different armatures or sheets of tin foil are connected, respectively, copper ribbon or other suitable terminals 24 and 25. To the terminal 24 is electrically connected the flexible wire or conductor 26 which connects also with the interiorly screw threaded and exteriorly roughened metal insert 27. Conductor 26 is also electrically connected with the interiorly screw threaded and exteriorly roughened metallic insert 28. The other condenser terminal 27 is electrically connected with the flexible wire or other conductor 29 which electrically connects with the exteriorly roughened insert 30. The condenser with its terminals 24 and 25, the conductors 26 and 29 and the inserts 27, 28 and 30, together with the additional exteriorly roughened insert 31, are placed in a mold and surrounded by plastic or powdered condensite, bakelite or equivalent moldable insulating material, or any other suitable type of insulating material, and then subjected to hydraulic or other suitably high pressure, preferably with the application of suitable heat for suitable length of time, with the result that a condenser unit is formed in which the condenser 23 is completely and entirely surrounded or housed in the insulating material 32, the pressure which caused the flowing together of the condensite, bakelite or other material serving also greatly to compress the condenser 23, bringing the neighboring armatures with intervening dielectric into very compact relation, with resultant relatively high capacity as compared with the amount of tin foil or other armature material or dielectric employed. The condenser so inclosed in a sealed and rigid housing is thoroughly water-proof and otherwise advantageously protected and shielded and held in the compressed state in which it has the relatively great capacity referred to.

The condenser unit is secured to the base 1 by the screws 33 and 34, the former extending through the hole in the insert 31 and threaded into the base plate 1, and the latter

similarly extending through the hole in the insert 30 and threaded into the base plate 1. Inasmuch as one terminal, namely, 25, of the condenser is connected by conductor 29 to the insert 30, the insert 30 becomes electrically connected with the base plate 1, one terminal of the condenser 23 therefore being in effect grounded or connected to the frame of the apparatus, to which is also electrically connected, as aforesaid, the movable interrupter contact 16. The aforesaid screw 21 threads into the insert 28 and clamps or holds the member 19 firmly to the condenser unit in substantial alinement with the lug or ear 35 thereof. In consequence the stationary interrupter contact 18 is in electrical communication through the member 19 with the insert 28, which is insulated from plate 1, and through the conductor 26 with the other terminal 24 of the condenser. The insert 27, serving as binding post structure or a part thereof, is in a second lug or ear 36 of the condenser unit, between which and the washer 37 is clamped a wire or conductor by action of the screw 38 which threads into the aforesaid insert 27. The wire held by the screw 38 and washer 37 is therefore in effect connected through the interior of the condenser unit through the conductor 26 with the stationary interrupter contact 18, the conductor 26 at the same time connecting the other terminal 24 of the condenser with the stationary interrupter contact 18. Accordingly the condenser 23 is as usual bridged across or shunted around the break between the contacts 16 and 18 when they are separated by action of the cam 4.

For an illustration of one of the circuit arrangements in which my structure may be employed, reference is had to Fig. 5, where in P is the primary of an induction coil whose high tension secondary S connects through a distributor, as well understood in the art, with the spark plugs of the various cylinders of the internal combustion motor. One terminal of the primary P connects through the switch s and the battery or other source of current B with the frame or ground F, while its other terminal connects through any suitable fixed or variable resistance R, which may be omitted, with the conductor 39, which is held under the washer 37 by screw 38 and thereby connected with the condenser unit insert 27. The base 1 is also shown grounded or connected to the mass or frame F. It is accordingly seen that the condenser 23 is bridged across the interrupter contacts 16 and 18 as usual in interrupter systems.

By structure of the character hereinbefore described, it is possible at once to suitably house and inclose the condenser and protect it mechanically and shield it from moisture and to employ the housing or condenser unit as a whole as a structural member in inter-

rupter mechanism for supporting and suitably insulating one of the interrupter contacts. In addition other advantages result from my structure, as will be apparent to those skilled in the art who will be able, without departure from the spirit of my invention, to modify my structure in various respects and apply my invention in various forms.

10 What I claim is:

1. The combination with an ignition coil, of interrupter structure comprising relatively movable interrupter contacts, a base member supporting one of said contacts, a 15 condenser unit comprising a condenser inclosed in a housing of insulating material, a second interrupter contact supported upon said insulating material and connected with one terminal of said condenser, a second 20 terminal of said condenser connected with said first named interrupter contact, and a connection from said ignition coil to one terminal of said condenser and inclosed within said insulating housing to said second 25 interrupter contact.

2. The combination with an ignition coil, of interrupter structure comprising relatively movable interrupter contacts, a conducting base member supporting and connected to one of said contacts, a condenser 30 unit comprising a condenser in a rigid housing of insulating material, means securing said unit and connecting one terminal of said condenser to said base member, a second interrupter contact supported upon said condenser unit and insulated thereby from said base member, a connection from the second terminal of said condenser to said second interrupter contact, and a connection from 35 said ignition coil to said second interrupter contact inclosed within said insulating material.

3. The combination with an ignition coil, of interrupter mechanism comprising relatively movable interrupter contacts, a base member supporting one of said contacts, a unit of insulating material secured to said base member, a conducting element carried by said insulating material, a member supporting a second interrupter contact secured to said element, a condenser inclosed in said insulating material and having one terminal connected to said element, and a connection between the other terminal of said condenser and first named interrupter contact.

4. The combination with an ignition coil, of interrupter mechanism comprising relatively movable interrupter contacts, a conducting base member supporting and connected to one of said interrupter contacts, a unit of insulating material, a conducting element carried thereby, a member supporting the second interrupter contact secured to said element, a second conducting element carried by said insulating material, means

coöperating with said second element to secure said unit to said base member and to connect said second element to said base member, and a condenser housed within said unit and having its terminals connected, respectively, to said elements. 70

5. The combination with an ignition coil, of interrupter mechanism comprising relatively movable interrupter contacts, a base member supporting one of said contacts, a unit of insulating material secured to said base member, said unit having a lug, an insert in said lug, a member carrying the second interrupter contact held on said lug by said insert, a condenser within said unit and having terminals connected, respectively, with said insert and with the first named interrupter contact. 75

6. The combination with an ignition coil, of interrupter mechanism comprising relatively movable interrupter contacts, a conducting base member supporting and connected to one of said contacts, a unit of insulating material, a condenser within said unit, an insert in said unit connected with one terminal of said condenser and with said base member, a pair of inserts electrically connected with each other within said insulating material and with the second terminal of said condenser, and a member held to one of said pair of inserts and carrying the second interrupter contact. 80 85 90 95

7. Interrupter structure comprising relatively movable contacts, a base member on which one of said contacts is supported, rotary cam structure for causing relative movement of said contacts, a unit of insulating material having lugs between which said cam structure is located, inserts in said lugs insulated from said base member and connected to each other within said insulating material, one of said inserts comprising binding post structure, a conducting member secured to the insert in one of said lugs and carrying the second interrupter contact, 100 105 110 a condenser within said insulating material, one terminal of said condenser connected to said conducting member, and an insert in said insulating material connected to the second terminal of said condenser. 115

8. Interrupter structure comprising relatively movable interrupter contacts, a conducting base member carrying and connected to one of said contacts, a condenser molded in a rigid housing of insulating material, a 120 conducting member carrying the second interrupter contact supported on said insulated housing, means securing said housing to said base member and connecting a condenser terminal thereto, and means within said insulating material connecting the second terminal of said condenser with said conducting member. 125

9. Interrupter structure comprising relatively movable interrupter contacts, a con- 130

ducting base member carrying and connected to one of said contacts, a condenser molded in a rigid housing of insulating material, a conducting member carrying the second interrupter contact supported on said insulated housing, means securing said housing to said base member and connecting a condenser terminal thereto, means within said insulating material connecting the second terminal of said condenser with said conducting member, binding post structure carried by said insulating material and insulated thereby from said base member, and a connection within said insulating material from said binding post structure to said conducting member.

10. Interrupter mechanism comprising relatively movable interrupter contacts, a base member carrying one of said contacts, a housing of insulating material, a condenser within said housing, a conducting member supported by said housing carrying the second interrupter contact and adjustable on said housing, and connections from the terminals of said condenser to said interrupter contacts.

11. Interrupter structure comprising relatively movable interrupter contacts, a base member carrying one of said contacts, a housing of insulating material carried upon said base member, a condenser within said housing, and a second interrupter contact supported upon said housing.

12. The combination with an induction coil, of interrupter structure comprising relatively movable interrupter contacts, a grounded conducting base member supporting and electrically connected to one of said contacts, a housing of insulating material carried on said base member, a condenser within said housing, one terminal of said condenser being connected to said base member, a second of said interrupter contacts supported on said housing, and electrical connections from the primary winding of said induction coil to the second terminal of said condenser and to the second of said interrupter contacts.

13. The combination with an induction coil, of interrupter structure comprising relatively movable interrupter contacts, a conducting base member supporting and connected to one of said contacts, a housing of insulating material carried on said member, a condenser within said housing, a second interrupter contact carried upon said housing and insulated from said member, one terminal of said condenser connected to said member, said member connected in the primary circuit of said coil, and said second contact connected to the second terminal of said condenser.

In testimony whereof I have hereunto affixed my signature this 24 day of June, 1919.

WILLIAM H. RICHTER.
